UNITED STATES PATENT OFFICE.

GEORGE N. EINSELE, OF CHICAGO, ILLINOIS, ASSIGNOR TO REUBEN W. NEWTON AND HARRISON F. JONES, OF CHICAGO, ILLINOIS.

SIGHT-FEED FOR LUBRICATORS.

No. 820,922.

Specification of Letters Patent.

Patented May 15, 1906.

Application filed March 17, 1905. Serial No. 250,672.

To all whom it may concern:

Be it known that I, GEORGE N. EINSELE, a citizen of the United States of America, and a resident of Chicago, Cook county, Illinois, have invented a certain new and useful Improvement in Sight-Feeds for Lubricators, of which the following is a specification.

My invention relates to sight-feeds for lubricators; and it relates more particularly to sight-feeds employed on locomotive-boilers and in similar situations, inasmuch as the ordinary glass-tube sight-feeds employed in such cases are subjected to harsher usage and are consequently more liable to be broken.

My invention contemplates a sight-feed adapted to be used as a substitute for the ordinary glass tube. Instead of being more or less frangible, however, as is the case with the ordinary glass tube, my improved sight-feed is constructed almost wholly of metal, or at least is so thoroughly reinforced with metal that all danger of its being broken is precluded or greatly reduced.

Preferably it consists of a hollow body provided at front and rear with glass walls of such size and thickness as not to be readily broken, and the top of the said body is provided with a boss adapted to engage the upper fitting of the lubricator, while the bottom of the body is provided with a similar boss adapted to engage the lower fitting, and with this construction the ends of the said top and bottom bosses are adapted to simulate the upper and lower ends of an ordinary glass tube. In this way my improved sight-feed is, as previously stated, of a substantially non-breakable character, but at the same time adapted to be used as a substitute for the ordinary glass tube, and it will be understood, of course, that the combination of glass and metal reinforcing means may be varied or changed in various ways, so that the sight-feed as a whole will be capable of use as a substitute for the ordinary glass tube without departing from the spirit of my invention.

The nature and advantages of my invention will, however, hereinafter more fully appear.

In the accompanying drawings, Figure 1 is an enlarged front elevation of the said sight-feed, showing its connection with the side of the lubricator. Fig. 2 is an enlarged per-

spective of my improved sight-feed. Fig. 3 is an enlarged vertical section of the sight-feed shown in Fig. 2. Fig. 4 is a section on the line 5 5 in Fig. 3. Fig. 5 is a plan of the sight-feed shown in Fig. 2.

As shown, the lubricator has an upper fitting C and a lower fitting D, the same communicating laterally with the body of the lubricator in the usual and well-known manner. The sight-feed E has its upper and lower ends secured to said fittings by means of the usual adjusting or clamping devices and is applied to the said fittings in the same manner that the ordinary glass tube would be employed and adjusted into place—at least as far as the method of attaching the upper and lower ends of the feed is concerned. Referring to Figs. 2 to 5, inclusive, it will be seen that the said sight-feed comprises a hollow body e, having its opposite ends provided with threaded portions e¹, adapted to receive the threaded clamping rings or caps e². It will also be seen that the said body is provided at opposite ends with the shoulders e³, these shoulders being adapted to serve as seats for the circular or disk-like glass walls e⁴. When the parts are assembled, the clamping rings or caps e² screw upon the said body and bear upon the said glass members, so as to clamp the latter tightly against the said shoulders or seats. The top of said body is formed with an internally-threaded socket e⁵, adapted to receive the threaded lower end portion of the boss or cylindrical member e⁶, it being observed that the upper end of said boss or cylindrical member is preferably provided with internal notches e⁷, adapted to receive a tool for screwing the boss or cylindrical member into place in the top of the said body. The lower boss or cylindrical member e⁸ is preferably made integral with the said body and may be provided internally with a small notch or recess e⁹, adapting it for easy insertion in the fitting D, providing the lubricator is of that type in which the lower fitting is provided with an upwardly-projecting nozzle, from which the globules of oil are allowed to escape and rise upwardly through the water in the sight-feed. Thus constructed it will be seen that the said sight-feed is hollow from top to bottom, its middle portion, however, being slightly enlarged to provide the chamber between the two transparent members e⁴. Consequently the oil can rise through

the water in the sight-feed, and as the globules pass through the chamber e^{10} they can be observed readily through one of the windows or glass walls e^4 , it being understood that the sight-feed will be so placed that the globules will be illuminated, either by daylight or by artificial light, as soon as they enter the chamber e^{10} .

The method of adjusting the sight-feed into place is as follows: The boss or cylindrical member e^6 is unscrewed from the body. The lower end of the boss or cylindrical member e^8 is then inserted in place in the lower fitting D. After this the detachable or upper 15 per boss or cylindrical member e^6 is then dropped downwardly through the upper fitting C, the cap or nut c having been first removed for this purpose. A tool can then be applied to the upper end of the said upper 20 boss or cylindrical member for the purpose of screwing it into its socket in the top of the body e . In this way and as previously stated, the upper and lower ends of the said bosses or cylindrical members are adapted to 25 simulate the upper and lower ends of the ordinary glass tube. Consequently the sight-feed can be placed in any lubricator which is adapted to receive the ordinary glass tube or transparent sight-feed. In other words, my 30 improved sight-feed necessitates no change whatever in the construction of the lubricator, as it is adapted to be sold and used as a substitute for the ordinary glass tube, and at the same time, as previously stated, the 35 sight-feed is of a non-breakable or practically non-breakable character, inasmuch as it is composed almost wholly of metal, there being only enough exposed glass to permit the globules of oil to be observed as they pass 40 upwardly through the water.

What I claim as my invention is—

1. A sight-feed for lubricators, comprising a hollow body a plurality of oppositely-arranged transparent walls, and upper and lower attaching portions, said portions being adapted to simulate the upper and lower ends of the ordinary glass tube, whereby the said sight-feed is adapted to be employed as a substitute for the said glass tube the said 50 sight-feed having an inlet-passage at its lower end and an outlet-passage at its upper end.

2. A sight-feed for lubricators, comprising upper and lower metal attaching portions, an intermediate portion and transparent means 55 permitting the globules of oil to be observed, said upper and lower portions being adapted to simulate the upper and lower ends of the

ordinary glass tube, whereby the said sight-feed is adapted for use as a substitute for the 60 said glass tube, the said sight-feed having an inlet-passage at its lower end and an outlet-passage at its upper end.

3. A sight-feed for lubricators, comprising upper and lower metal attaching portions, an 65 intermediate portion and transparent means for viewing the globules of oil as they pass upwardly through the sight-feed, said attaching portions being adapted for establishing the desired connection between the sight- 70 feed and the structure of the lubricator the said sight-feed having an inlet-passage at its lower end and an outlet-passage at its upper end.

4. A sight-feed for lubricators, comprising 75 a hollow body, front and rear with detachable transparent walls, and vertically-extending metal attaching portions, said attaching portions being adapted for establishing connection between the sight-feed and the structure of the lubricator the said sight-feed having an inlet-passage at its lower end and an outlet-passage at its upper end.

5. A sight-feed for lubricators, comprising 80 a hollow body, oppositely-arranged detachable transparent members through which the globules of oil may be observed, and having cylindrical and vertically-disposed top and bottom metal attaching portions adapted to simulate the upper and lower ends of an ordinary glass tube, whereby the said sight-feed is adapted for use as a substitute for the 85 said ordinary or usual sight-feed the said sight-feed having an inlet-passage at its lower end and an outlet-passage at its upper 90 end.

6. A sight-feed for lubricators, comprising 95 a metal body, front and rear detachable glass walls through which the globules of oil may be observed, a downwardly-extending integral attaching portion, and an upwardly-extending detachable attaching portion, said attaching portions being of metal and adapted to simulate the upper and lower end portions of the ordinary glass tube, whereby the 100 sight-feed is adapted to be used as a substitute for the said ordinary or usual sight-feed the said sight-feed having an inlet-passage at its lower end and an outlet-passage at its upper end.

Signed by me at Chicago, Cook county Illinois, this 8th day of March, 1905.

GEORGE N. EINSELE.
